(57) **CLAIM**

The ornamental design for a slider for slide fastener as shown and described.

DESCRIPTION

FIG. 1 is a perspective view of a slider for slide fastener showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof with the pull tabs erected.

The broken lines in the drawings are for the purpose of illustrating portions of the slider for slide fastener that form no part of the claimed design.

1 Claim, 8 Drawing Sheets
